UNITED STATES PATENT OFFICE.

AUGUSTUS B. KNOWLTON, OF COLUMBIA, SOUTH CAROLINA.

SAFETY-ENVELOP.

No. 910,692.

Specification of Letters Patent.

Patented Jan. 26, 1909.

Application filed June 23, 1908. Serial No. 439,987.

To all whom it may concern:

Be it known that I, AUGUSTUS B. KNOWLTON, a citizen of the United States, residing at Columbia, in the county of Richland and State of South Carolina, have invented certain new and useful Improvements in Safety-Envelops, of which the following is a specification.

This invention relates to the manufacture of envelopes and other receptacles, and more particularly to that type of envelop or receptacle which has its sealing portions so shielded that having once been sealed it can not be opened without destroying the envelop and thus give evidence of its having been opened; such envelopes being especially useful in the transportation of money, valuable papers, etc., by mail or express.

The object of the invention is to produce an envelop of the above type which can be cheaply manufactured and which, when completed, is practically as simple, light and neat in appearance as the ordinary envelop.

The invention will best be understood by the following description, taken in connection with the accompanying drawings, in which—

Figure 1 is a plan view of the blank from which my envelop is constructed; Fig. 2 is a similar view of the same showing the left hand flap folded upon itself upon the main section; Fig. 3 is a similar view of the same showing the right hand flap folded over on the other flap and threaded on a guide tongue carried thereby; Fig. 4 is a view of the completed envelop; and Fig. 5 is a cross-section taken on the line 5—5 of Fig. 4.

Referring to the drawings, 1 is the main section forming the face of the envelop and having a flap on each side, as shown. The flap 2 consists of an upper and a lower part, the lower part 6 having a tongue 7 which, when the lower part is folded upon the upper part, passes through a slot 8 in the upper part formed by stamping out the guide tongue 9 hereinafter mentioned.

The flaps 3 and 4 each have a slot 8 which, when folded upon the main section, as presently explained, register with each other and are threaded upon the aforementioned guide tongue 9 which projects outward from the exposed face of flap 2 when it is folded on the main section, as shown in Fig. 2. The top flap 5 has a tongue formed on it which carries the mucilage or other sealing substance.

The operation of forming the envelop from

the blank is as follows: The lower part of flap 2 is folded upon the upper part along line 10, and the projection 7 slipped through slot 8, thus forming a pocket of flap 2. The flap 60 is then folded in on the main section 1 with guide tongue 9 and projection 7 extending out from the face of the flap, as shown in Fig. 2. Flap 3, and then flap 4 are each in turn folded in on the main section, the guide 65 tongue 9 threading through each as they are folded over, and the envelop is then ready for use.

To seal the envelop the tongue 5 is moistened and passed through the slots 8 formed 70 in the several flaps, being guided by the upwardly extending guide tongue 9 into the pocket formed in flap 2, when it is sealed to the wall 6. It will be seen from this that the envelop is provided with a pocket 75 into which the sealing tongue passes, so that there is no danger of the tongue sticking to the letter, and that the guide tongue for guiding the sealing tongue into the pocket is also utilized for securing the flaps together. 80 An envelop thus constructed can not be opened by the ordinary "steaming" process, there being two thicknesses of envelop, and the letter on one side of the mucilage, and four thicknesses of the envelop on the 85 other side.

If desired, a little glue may be put on the inner end of flap 3 to assist in holding it to flap 4, but this is not necessary.

It will be noted that the projection 7 90 which extends up through slot 8 serves no special purpose after it passes through the slot 8 other than preventing the sealing tongue from catching on the upper edge of part 6 which it otherwise might do if projection 7 did not pass through the slot. 95

Having described my invention, what I claim as new and desire to secure by Letters Patent of the United States is,—

1. An envelop blank having a flap composed of an upper part formed with a slot and a lower part provided with a tongue, the lower part arranged to be folded upon the upper part to form a pocket therebetween with said tongue projecting through said 105 slot, a guide tongue formed on the upper part of said flap adjacent said slot, a top flap having a sealing tongue to enter said pocket through said slot between said tongues, and coöperating flaps to complete 110 the envelop.

2. An envelop having a top flap with a

sealing tongue, side and bottom flaps, a
pocket formed in one of said flaps by fold-
ing the lower extremity of the flap upon the
upper part and passing said lower extremity
5 through an opening in said upper part of
the flap, a guide tongue stamped up from
said upper part to form the opening, and
slots in the remaining flaps adapted when
folded to coincide with each other and be

threaded over said guide tongue so that the 10
latter projects therethrough to guide the
sealing tongue into the pocket.

In testimony whereof I have affixed my
signature in presence of two witnesses.

AUGUSTUS B. KNOWLTON.
